UNITED STATES PATENT OFFICE.

WILBUR A. COCHRANE, OF SEA CLIFF, NEW YORK.

ACETYLENE-LAMP.

1,178,496.

Specification of Letters Patent. Patented Apr. 11, 1916.

Application filed November 5, 1914. Serial No. 870,426.

To all whom it may concern:

Be it known that I, WILBUR A. COCHRANE, a citizen of the United States, residing at Sea Cliff, county of Queens, and State of New York, have invented certain new and useful Improvements in Acetylene-Lamps, fully described and represented in the following specification and the accompanying drawings, forming a part of the same.

10 This invention relates to an improvement in miners' acetylene cap lamps. In lamps of this kind, as is well known to those skilled in the art, the burner orifice must be extremely small in diameter and, because of the necessarily small size of the lamp, the burner is relatively close to the gas-generating chamber; consequently, as the gas in the generating chamber carries a considerable quantity of floating particles of lime, or 15 carbid, and these particles are very fine, the burner orifice is frequently obstructed by such particles.

It has been the common practice heretofore to make an acetylene burner having its 20 outer end formed as an inward-projecting or reentrant cone, the inner surface of which is also conical, the burner orifice being at the apex of the cone, so that fine particles carried by the gas tend to be deflected away 25 from the orifice and accumulate toward the base of the cone. Such a type of burner is shown, for example, in British Patent 9762 of 1897. By this construction, only 30 those particles which strike exactly at the burner orifice can serve to clog the same. With a construction of this kind, it is advisable to have the burner readily removable from the lamp, so that the inside of the burner may be freed from the accumulated 35 particles which collect inside around the base of the cone.

The present invention relates to a structure embodying a burner and a reflector so arranged and constructed that the burner, 40 while capable of convenient removal at intervals, is so securely attached to the lamp as not to be in danger of accidental displacement from the burner tube. Also, in the preferred embodiment of the invention, 45 a reflector support is used and the burner is so arranged that it serves to hold the reflector and its support firmly in place.

In the best embodiment of the invention, 50 the burner is provided with a slot extending from the exterior conical cavity of the burner to the margin, this slot serving to

admit air freely to the conical portion of the burner and also serving for the insertion of a tool, such for example as a screwdriver, whereby the burner may be readily removed. Further, in small acetylene lamps it has been customary to use an open concave reflector, the burner being at or near the center of the reflector. With such a construction, any side drafts of air striking 60 the reflector are likely to be reflected to and concentrated in the flame, thereby tending to blow out the light.

An important feature of the present invention consists in providing a construction 70 in which the burner has a projecting portion or margin surrounding the burner orifice and extending over the reflector in such a way as to act as a baffle for any side drafts of air traveling over the surface of the reflector and toward the burner orifice, whereby such drafts are broken up and thrown outward axially of the reflector, thus preventing the flame from being extinguished.

The invention will first be described in 80 connection with the accompanying drawings, and then more particularly pointed out.

In the drawings,—Figure 1 is a side elevation, partly in section, of a miner's cap lamp, provided with the present invention; 85 Fig. 2 is a side elevation; and Fig. 3 a front view of one form of burner embodying some of the features of the present invention.

Referring to the drawings, 1 is the water reservoir, 2 the neck, 3 the screw thread, 4 the skirt, and 5 the carbid receptacle, of a well known type of miner's acetylene cap lamp. From this lamp projects a burner tube 6, which, in the present example, is larger than the burner tubes usually employed with such a type of lamp, the outer end being screw-threaded on its exterior. On this threaded portion is screwed a burner 7, having an outward-projecting portion, collar, or flange 8. The lamp is provided with a reflector 9, which has a central opening, through which the burner extends, this opening having a less diameter than that of the projecting portion 8. Around the burner tube and between the lamp body and the reflector is placed a reflector supporting device 10, which, in the present example, is most conveniently pressed from sheet metal. This supporting device has its bottom formed concave, to 100 generally fit the curvature of the lamp, and is provided with a plurality of openings 11

for the circulation of air, whereby the parts are kept cool. The front of the reflector supporting device has its margin formed to make a contact with the back of the reflector 5 in such a way as to efficiently support the said reflector firmly. When the burner is inserted through the opening at the center of the reflector and is screwed firmly onto the end of the burner tube, as shown in Fig. 10 1, the reflector is pressed tightly against its supporting device 10, and the latter is pressed against the lamp, so that the reflector is held tightly in place and supported in such a manner that it will not readily be 15 bent by accidental blows.

The front end of the burner is provided with a reentrant conical wall, as indicated at 12, the apex of the cone having a burner orifice which, in lamps of this type, is very 20 small. Particles of carbid, or lime, escaping from the lamp into the burner tube will be carried by the outflowing gas toward the burner orifice, but, in general, will not be likely to strike exactly in the orifice and 25 hence when striking at any side thereof will be deflected toward the front of the burner and accumulate inside the same, near the base of the conical portion.

In order that the burner may be readily 30 removed, it is so formed as to permit the application of a suitable tool for such removal. This may be done by providing the burner with a polygonal periphery to receive a wrench, or with slots for a screw-driver. 35 Most advantageously, it may be provided with both such means, as is shown in Figs. 2 and 3.

An important feature of this invention 40 consists in arranging the slots for the screw-driver so that they extend from the conical recess at the outer end of the burner toward the periphery of the latter, thereby serving not only to receive a screw-driver but also to permit a copious inflow of air to the 45 flame, thus insuring perfect combustion of the acetylene gas. When it is desired to remove the burner for the purpose of cleaning it, as by removing the accumulated carbid or lime particles, either a wrench may be 50 applied to the burner, or a screw-driver may be inserted in the slots. As this operation of cleaning a burner does not require to be done at very frequent intervals, the inconvenience of using a tool to remove the 55 burner is so slight as to be negligible. On the other hand, owing to the necessity for the use of such tools, and the screw-threaded connection between the burner and the burner-tube, the danger of an accidental re-

moval of the burner is avoided. It will be 60 noted that the projecting or collar portion 8 of the burner makes a sufficient engagement with the reflector to secure the reflector firmly in place. Also, this projecting portion 8 stands up from the reflecting surface 65 of the reflector, so that any side drafts of air moving along the reflecting surface will be prevented from flowing straight to the flame, and will be deflected forward so as not to act transversely on the flame. In this 70 way, the danger of extinguishing the flame is avoided.

What I claim is:

1. In an acetylene cap lamp, the combination, with the lamp-body, with the burner-tube projecting therefrom and having an exteriorly threaded end, a reflector provided with an opening, and a reflector support bearing against the lamp, of a burner extending through the opening in the reflector, said burner having interior screw-threads arranged to engage the threads of the burner and having a laterally extending portion at its front end arranged to engage the outer face of the reflector to press the latter against its support, said burner having a burner-orifice and a conical recess into which the burner orifice opens at a point back of the front surface of said laterally projecting portion. 75 80 85 90

2. In an acetylene cap lamp, the combination, with the lamp-body, a burner-tube projecting therefrom and having an exteriorly threaded end, a reflector provided with an opening, and a reflector support bearing against the lamp, of a burner extending through the opening in the reflector, said burner having interior screw-threads arranged to engage the threads of the burner and having a laterally extending portion at its front end arranged to engage the outer face of the reflector to press the latter against its support, said burner having a burner-orifice and a conical recess into which the burner orifice opens at a point back of the front surface of said laterally projecting portion, said burner also having a transverse slit extending outward from said conical recess across the laterally projecting portion to the periphery 100 105 110 of the latter.

In testimony whereof, I have hereunto set my hand, in the presence of two subscribing witnesses.

WILBUR A. COCHRANE.
